UNITED STATES PATENT OFFICE.

ALLEN A. CANTON, OF NEW YORK, N. Y., ASSIGNOR TO CANTON FAN HEATER CO., A CORPORATION OF DELAWARE.

FAN.

1,348,477.

Specification of Letters Patent.

Patented Aug. 3, 1920.

Application filed August 20, 1919. Serial No. 318,784.

To all whom it may concern:

Be it known that I, ALLEN A. CANTON, a citizen of the United States of America, residing at the city, county, and State of New York, have invented new and useful Improvements in Fans, of which the following is a specification.

This invention relates to fans.

The object of the invention is to provide an electric fan having an electric heating element coöperating therewith with means for interrupting the current of air from the fan so that the current of air passes over or through the heating element in impulses, instead of in a steady current.

A further object is to provide means for varying the period of interruption of the current of air and independently operated means for varying the speed of the fan and the flow of current to the heating element.

Where a resistance is subjected to a constant current of air, it will not attain the maximum glow or incandescence which it would attain without the current of air being interrupted. By interrupting the current of air for a short period of time the glow or incandescence of the resistance will be increased so that, when the current of air is resumed, more heat will be taken up in a given time and diffused by the current of air.

I am aware that patents have been granted, for instance Patent No. 676949, of June 25, 1901, covering the combination of a motor-driven fan and a resistance, but my improvement consists in interrupting the current of air for the purposes described.

The invention consists in the construction, combination and arrangement of parts, as herein illustrated, described and claimed.

In the accompanying drawings, forming part hereof, is illustrated a form of embodiment of the invention, in which drawings similar reference characters designate corresponding parts, and in which:

Figure 1 is a side elevation, partly in section;

Fig. 2 is an elevation of the heating element;

Fig. 3 is an elevation of the rear wall of the fan casing; and,

Fig. 4 is an elevation of the shutter used in the construction.

Referring to the drawings, 1 designates a base, supporting a motor 2, on the shaft of

which is disposed a fan 3, all of these elements being of common and well-known construction.

Disposed around the fan 3 and supported by the casing of the motor 2 is a casing 4, provided with segmental slots 5 in its rear wall and having its opposite side open.

Disposed across the open end of the casing 4 are suitable resistance wires 6, supported on rods 7 carried by a rectangular frame 8, adapted to be slipped into the open end of the casing 4 and to be retained therein by friction. A suitable guard 9 is used to prevent accidental contact with the resistance wires 6 when they are heated.

A shutter 10 comprising a thin disk is provided with segmental slots 11, corresponding in size and arrangement with relation to its periphery to the segmental slots 5 in the casing 4. The central opening of the shutter 10 has secured adjacent thereto a cone-shaped split sleeve 12 arranged to be adjustably retained by friction on a cone 13 on the shaft of the motor so that the disk 10 may rotate at the speed of the fan-shaft 13 or at a variable speed below the fan-shaft.

Wires 14 are secured to the resistance wires 6 and are so arranged as to be controlled by a switch 15, so that a varying volume of current may pass therethrough to vary the heating of the resistance wires 6.

The wires 14 at a point past the switch 15 are connected to the wires 16 which are used as feed wires to the motor 2. By this arrangement the electric current to the resistance wires 6 may be varied or cut off and the fan operated as usual.

A suitable switch 17, of common construction is arranged to vary and control the speed of the fan 3. By adjusting the shutter 10 longitudinally of the motor shaft the speed of the shutter may be varied, as at its point furthest removed from the fan the shutter is simply loosely mounted, and as the friction thereof on the shaft is increased by forcing it toward the right-hand of Fig. 1 the speed of the shutter will be correspondingly increased.

When the slots 11 register with the slots 5 a current will be permitted to be forced out of the open end of the casing 4 and over the resistance wires 6. When the slots 5 and 11 do not register, the current will be materially reduced, so the current from the fan 3 is by impulses, permitting the resistance wires 6 to become more highly incan-

descent between the impulses than if a steady current of air was used by the fan 3.

Having thus fully described my invention, what I claim as new and desire to secure by Letters Patent is:

- 5 1. In combination with a fan and a heating element disposed in the path of a current of air from the fan, means for interrupting the current of air.
- 10 2. In combination with a fan and a heating element disposed in the path of a current of air from the fan, means for periodically interrupting the current of air.
- 15 3. In combination with a fan and a heating element disposed in the path of a current of air from the fan, means effected by the operation of the fan for interrupting periodically the current of air.
- 20 4. In combination with a fan, a heating element disposed in the path of movement of a current of air from the fan, a source of electrical current for operating the fan and the heating element, and means for interrupting the current of air from the fan.
- 25 5. In combination with a fan, a heating element disposed in the path of movement of a current of air from the fan, a source of electrical current for operating the fan and the heating element, independently operable means for controlling the flow of electric current to the fan and heating element, and means for interrupting the current of air from the fan.
- 30 6. In combination with a fan, a heating element disposed in the path of movement of a current of air from the fan, a source of electrical current for operating the fan and the heating element, means for interrupting the current of air from the fan, and means for varying the frequency of the interrupting means.
- 35 7. In combination with a fan, a heating element disposed in the path of movement of a current of air from the fan, a source of electrical current for operating the fan and the heating element, independently operable means for controlling the flow of electric current to the fan and heating element, means for interrupting the current of air from the fan, and means for varying the frequency of the interrupting means.
- 40 8. In combination with a fan and a heating element, a casing disposed around the fan and arranged to hold the heating element, and provided with slots in its rear wall, and a shutter arranged to be operated by the operation of the fan and provided with slots corresponding to the slots in the casing.
- 45 9. In combination with a fan and a heating element, a casing disposed around the fan and arranged to hold the heating element, and provided with slots in its rear wall, and a shutter arranged to be operated by the operation of the fan and provided with slots corresponding to the slots in the casing, and means for varying the speed of rotation of the shutter with relation to the fan.
- 50 10. In combination with a fan, a casing disposed over the fan and provided with slots in its rear wall, a heating element carried by the open end of the casing, a cone disposed on the fan shaft, a split cone-shaped sleeve adjustably disposed on the cone, and a shutter secured to the sleeve and provided with slots corresponding to the slots in the fan casing.
- 55 11. In testimony whereof I have signed my name to this specification.

ALLEN A. CANTON.
